B. P. HANSON,
TONGUE CONSTRUCTION.
APPLICATION FILED OCT. 3, 1914.

1,134,969.

Patented Apr. 6, 1915

UNITED STATES PATENT OFFICE.

BENNIE P. HANSON, OF MONTICELLO, IOWA, ASSIGNOR OF ONE-HALF TO LONE GRENDAR, OF BANCROFT, IOWA.

TONGUE CONSTRUCTION.

1,134,969.

Specification of Letters Patent.

Patented Apr. 6, 1915.

Application filed October 3, 1914. Serial No. 864,744.

To all whom it may concern:

Be it known that I, BENNIE P. HANSON, a citizen of the United States, residing at Monticello, in the county of Jones and State 5 of Iowa, have invented certain new and useful Improvements in Tongue Construction; and I do hereby declare the following to be a full, clear, and exact description of the invention, such as will enable others 10 skilled in the art to which it appertains to make and use the same.

This invention relates to improvements in tongue construction for wagons and trucks, and particularly to the tongue-hound.

15 My object is to furnish a tongue-hound which is of light and durable construction and one that can be adjusted to meet the requirements of any running gear construction.

20 In the drawings herewith which are made a part of this application, Figure 1 is a plan view of one of my wagon tongues and hound. Fig. 2 is a transverse sectional view on the lines 2-2 of Fig. 1. Fig. 3 25 is a longitudinal sectional view on the line 3-3 of Fig. 1. Figs. 4 and 5 are views showing varied forms of openings in the adjusting bars, and Fig. 6 is a plan view of a wagon tongue and hound of varied and 30 lighter construction.

In the specific description of the drawing numerals will be used to indicate the various parts and the same numeral will be used to indicate the same part throughout 35 the various views of the drawing.

My invention comprises a tongue 4 and the tongue-hound which latter comprises a plurality of bolts and bars more fully described hereinafter.

40 The hound comprises two convergent members 5 and 5^a, each of said members having two adjusting bars 6 and 6^a secured thereto in any preferred manner or they may be made integral therewith, the said 45 adjusting bars 6 and 6^a having a plurality of perforations, or a continuous slot as preferred. The said bars are positioned on the said members 5 and 5^a so that they extend inwardly in a line parallel with the plane 50 of the axle of the wagon and to an extent equal to approximately one third of the distance between the two members 5 and 5^a, thus providing a space between the ends 55 of the said bars 6 and 6^a in which the tongue is positioned.

On the tongue 4 adjacent the point 7 bearing the doubletree, a plate 8 having the shape of an isosceles triangle is secured with the longest point 9 of the triangle on the tongue, the other points 10 and 11 extending on either side thereof. The forward end including the point 9 is shaped to conform to the shape of the tongue, the rear portion being left flat to furnish a proper bearing for the double tree. 60

A plate 13 of the same shape as the plate 8 is secured to the under side of the tongue immediately below and registering with the plate 8, the said plate 13 being shaped to fit the underside of the tongue and embrace 70 it snugly throughout the length of the said plate 13 when in its operative position.

Attached to the points 10 and 11 by the bolts 12 are the members 14 and 14^a. The said members 14 and 14^a each comprise two 75 parallel bars 15 and 16 of equal dimensions, held in spaced relation by the bars 6 and 6^a to which the members 14 and 14^a are removably attached by bolts through an opening in the bars 15 and 16 and one of the 80 plurality of openings in the bars 6 and 6^a. The front ends of the bars 15 and 16 extend between the plates 8 and 13 at the points 10 and 11 and are secured thereto by means of the bolts 12 passing through both of the 85 said plates and the said bars, and additional openings 17 and 18 are provided near the corners of the triangular plates to provide means for adjustment at those points. Upon the upper surface of the bar 16 an eye 19 is 90 secured to receive the draft bolt 20 which passes through openings in the members 5 and 5^a, and also through an opening in the tongue, all of said openings and the said eyes 95 registering with openings in the front hound of the wagon through which the said draft bolt also passes to connect the tongue to the wagon.

Supporting the rear end of the tongue is a bracket comprising two bars, one of said 100 bars 21 being formed to snugly embrace the surface of the upper portion of said tongue and the ends thereof extending laterally to rest upon the bars 15 of the members 14 and 14^a, said bar 21 having a plurality of openings through the ends thereof. A duplicate 105 22 of said bar 21 is positioned under the end of the tongue, the said bars being held in spaced relation by the members 14 and 14^a to which the said bars are removably attached 110

by the bolts 23, and the auxiliary bolts 24 further aid in securing the bars 21 and 22 about the end of the tongue.

Fig. 6 illustrates a tongue hound of lighter construction than that contemplated in Fig. 1, embodying the elements of my construction in a modified form and showing means 25 for securing the tongue-hound to the running gear of a wagon which does not 10 have a front hound.

From the foregoing description it will readily be seen that a light, strong and easily adjusted tongue-hound is provided, one that may be carried in stock by dealers 15 and adjusted to the spread of the front hound of any make or size of wagon.

I desire it to be understood that I wish to comprehend in this application all substantial equivalents and substitutes which 20 may be considered as falling fairly within the scope of my invention.

Believing that the construction, advantages and operation of my invention have thus been made clearly apparent further 25 description is deemed unnecessary.

Having thus fully described my invention what I desire to secure by Letters Patent is;

1. A wagon tongue-hound, comprising a 30 pair of triangular plates; a pair of convergent bars having adjusting bars attached thereto and a plurality of openings through said adjusting bars; a bracket having latter-

ally extending ends, said ends having a plurality of openings therethrough; two pairs 35 of parallel bars, removably connected to said pair of plates and to the said bracket and the said adjusting bars, and a draft bolt, whereby the various parts of the tongue hound are connected with each other and also with the 40 front hound of a wagon.

2. The combination with a wagon tongue, of a tongue-hound comprising a pair of triangular plates attached to the upper and under surfaces of the said tongue; a pair of 45 convergent bars; a plurality of adjustment bars having a plurality of openings therethrough, said adjustment bars being connected to said convergent bars; two pairs of parallel bars held in spaced relation by the 50 said adjustment bars, each pair of said bars having an eye secured thereon; a bracket embracing the rear end of the said tongue, the ends of the bars comprising said bracket being held in spaced relation by the pairs 55 of parallel bars, and the said ends of the bars having a plurality of openings therethrough.

In testimony whereof I have signed my name to this specification in the presence of 60 two subscribing witnesses.

BENNIE P. HANSON.

Witnesses:
